UNITED STATES PATENT OFFICE

169,942

APPAREL BELT

Albertus W. Little, Campbell, Calif.

Application February 6, 1953, Serial No. 23,471

Term of patent 7 years

(Cl. D3—10)

To all whom it may concern:

Be it known that I, Albertus W. Little, a citizen of the United States, residing at Campbell, in the county of Santa Clara and State of California, have invented a new, original, and ornamental Design for an Apparel Belt, of which the following is a specification, reference being had to the accompanying drawings, forming a part thereof.

In the drawings:

I claim:

The ornamental design for an apparel belt, substantially as shown.

ALBERTUS W. LITTLE.
